UNITED STATES PATENT OFFICE.

EDWARD W. MCSHEEN, OF SCHENECTADY, NEW YORK, ASSIGNOR TO GENERAL ELECTRIC COMPANY, A CORPORATION OF NEW YORK.

CABLE-RETAINING SHROUD.

Application filed June 22, 1925. Serial No. 38,715.

My invention relates to electric switches and particularly to switches of the fluid break type having tanks which are adapted to be raised and lowered by means of a cable wound upon a drum. With such apparatus and when a steel cable has been used, difficulty has been experienced with the cable getting out of place on the drum when allowed to slack. It is an object of my invention to provide a simple and effective means which may be carried by the winding drum to overcome this difficulty by retaining the cable at all times in position on the drum.

My invention will be better understood from the following description taken in connection with the accompanying drawing, and its scope will be pointed out in the appended claims.

Referring to the drawing, Fig. 1 is a side elevation of a portion of an oil switch together with an attachment including my invention; Figs. 2 and 3 are end and side views respectively of the cable winding drum and shroud involving my invention and Fig. 4 is a fragmentary cross sectional view of the drum and shroud.

In Fig. 1 of the drawing I have shown my invention applied to a tank raising and lowering attachment for an oil switch. The switch is of well known construction, a part only of which is illustrated including portions of the frame 1 and the tank 2. The tank raising and lowering attachment 3 is adapted to be brought up to the switch 30 against which the arm 4 may bear to brace the attachment. The attachment has a drum 5 around which is wound the steel cable 6 which passes up over the pulley 7 at the top and thence to the switch where it is shown 35 passing over the pulley 8 to pulley 9 of the tank attaching block 10, to pulley 11 and back to the block 10. The drum 5 is shown adapted to be rotated by a hand crank 12 through worm gearing 13.

When the cable is allowed to slack as for example after the tank has been lowered to the floor the steel cable by reason of its resiliency is apt to get out of place on the drum and to prevent this I provide the drum with 45 the retaining shroud 15. This shroud may conveniently be formed of a strip of sheet metal, each end of the strip having laterally extending ears 16 through which pass the

bolts 17 thus forming an eye through which the cable passes. The body portion of the shroud is shown of such a width that it covers the cable when the same is wound up on the drum and it is retained laterally on the drum by the side flanges 18 thereof. As the drum is rotated to wind or unwind the cable the shroud rides loosely on the drum, the ends of the shroud being drawn together by bolts 17 only sufficiently to prevent the turns of the cable from springing out of place when the cable is allowed to slack. 65

While I have described only one embodiment of my invention, I do not wish to be limited to the particular form shown and described as it will be apparent that modifications therein may be made without departing from the scope of my invention as set forth in the appended claims.

What I claim as new and desire to secure by Letters Patent of the United States, is,—

1. In a device of the class described, a winding drum having side flanges, a cable secured at one end thereto and wound thereon, and means loosely engaging the cable wound on the drum and permitting the winding and unwinding thereof for preventing displacement of the cable from the drum when the cable is slackened, said means being retained in position on the drum by said flanges. 75

2. In a device of the class described, a winding drum, a metallic cable secured at one end thereto and wound thereon and means for preventing the displacement of the cable when slackened comprising a shroud loosely wrapped about the drum carrying the cable and having its ends connected together forming an eye through which the cable passes. 80

3. In an electric switch, a steel cable, a drum upon which the cable is adapted to be wound and unwound having side flanges, a sheet metal shroud having its end portions extending substantially parallel and its intermediate portion embracing the drum and cable thereon between the flanges, and means connecting the end portions of the shroud for adjusting the same on the drum. 95

In witness whereof, I have hereunto set my hand this 19th day of June, 1925.

EDWARD W. MCSHEEN.
